UNITED STATES PATENT OFFICE.

CORNELIUS MANDEVILLE, OF NEWARK, NEW JERSEY.

DESIGN FOR A SLEEVE-BUTTON.

SPECIFICATION forming part of Design No. 15,209, dated August 5, 1884.

Application filed June 2, 1884. Term of patent 7 years.

To all whom it may concern:

Be it known that I, CORNELIUS MANDEVILLE, a citizen of the United States, residing at Newark, in the county of Essex and State 5 of New Jersey, have invented a certain new and original Design for Sleeve-Buttons and other Similar Articles of Jewelry; and I do hereby declare the following to be a full, clear, and exact description of the invention, such as will 10 enable others skilled in the art to which it appertains to make and use the same, reference being had to the accompanying drawings, and to letters of reference marked thereon, which form a part of this specification.

15 Figure 1 is a plan of a sleeve-button or other piece of jewelry embodying my design, and Fig. 2 is a side elevation of the same, said figures being deemed sufficient to illustrate the nature of the design, which consists in the 20 sleeve-button or other similar article of jewelry having the configuration hereinafter described.

In said drawings, a represents a piece of jewelry with a letter-shaped protuberance, b, on 25 the surface c thereof. The letter-shaped projecting portions may have the configuration of any of the letters of the alphabet, and may be shaped in imitation of a cornstalk. In addition to the protuberances b, and commingled or apparently intertwined therewith, are husk or 30 leaf shaped projections d and protuberances e, in imitation of ears of corn.

It will of course be understood that the number of leaf and ear shaped protuberances may be varied to suit the initial employed and its 35 situation on the piece of jewelry.

What I claim is—

In a sleeve-button or other similar article of jewelry, the design which consists of an initial letter having protuberances in imitation of 40 ears of corn, and leaves or husks displayed therewith, as set forth.

In testimony that I claim the foregoing I have hereunto set my hand this 16th day of May, 1884.

CORNELIUS MANDEVILLE.
